NUT FOR AN EAR WIRE

George A. Armstrong, 314 Norwood Ave.,
Cranston, R.I.

Filed June 4, 1962, Ser. No. 70,410

Term of patent 3½ years

(Cl. D45—9)

F I G. 1

F I G. 2

F I G. 3

FIG. 1 is a top plan view of the ear wire nut showing my new design;

FIG. 2 is a side elevation thereof;

FIG. 3 is a bottom plan thereof.

The dominant feature comprises the outward flaring of the scalloped edge so that the scallops show in both plan and profile.

I claim:

The ornamental design for a nut for an ear wire, substantially as shown and described.
